UNITED STATES PATENT OFFICE

ALFRED EDWARD FLENLEY, OF LIVERPOOL, ENGLAND, ASSIGNOR TO ASSOCIATED TELEPHONE & TELEGRAPH COMPANY, OF CHICAGO, ILLINOIS, A CORPORATION OF DELAWARE

TELEPHONE SYSTEM

Application filed August 8, 1930, Serial No. 473,866, and in Great Britain August 9, 1929.

The present invention relates to automatic switches for use in telephone or like systems and is more particularly concerned with so-called connector or final selector switches 5 from the banks of which access is obtained to a wanted party's line. Where party line service is being provided it has been usual in the past to supply a special group of party line final selector switches which were different from those connecting only with individual lines in that they were provided with special ringing equipment capable of sending out the necessary ringing code for each subscriber connected to a party line. 10 Such schemes are inclined to be extravagant in cases where the number of party lines is small compared with the number of individual lines since economical use cannot be made of the special group of party line switches. 15 The object of the present invention is the provision of improved circuit arrangements for final selectors whereby switches of one type only may be made to function satisfactorily in connecting with lines of both classes. 20

According to one feature of the invention, in a final selector switch the operation of connecting with a party line serves to disconnect ringing current of the character used for signalling individual lines and render the switch 25 responsive to a further digit for selecting ringing current of the appropriate character.

According to a further feature of the invention, the setting of a final selector switch 30 in response to two digits automatically effects the connecting up of ringing current to the wanted line unless the digits are of predetermined value when a further digit is necessary to effect the connecting up of ringing current.

The invention will be better understood 35 from the following description of one method of carrying it into effect which should be taken in conjunction with the accompanying drawings of which Fig. 1 shows a final selector of substantially known type modified in

accordance with the principles of the invention by the addition of an auxiliary switch which establishes connection with the desired code ringing set, while Fig. 2 shows a suitable form of the code ringing set. It will be 40 understood that the invention is not limited to the precise arrangements shown and that various detail modifications such as will readily occur to those skilled in the art will come within its scope. 45

Referring now to Fig. 1, when the switch there shown is taken into use over line conductors 10 and 11, line relay A is operated and at armature a1 completes a circuit for relay B which also operates. Thereupon at 50 armature b1 it connects earth to release trunk conductor 12 in order to hold operated the preceding switches, at armature b2 prepares the circuit of the vertical magnet V, at armature b3 connects earth to conductor 13 in 55 order to start the ringing and tone current generator, at armature b4 prepares a holding circuit for relays F, G and H, and at armature b5 prepares a circuit for the lower winding of relay G. 60

No further circuit changes take place until the succeeding series of impulses is received whereupon relay A de-energizes intermittently and on each de-energization completes a circuit from earth, armatures a1 and b2, off normal springs N1, winding of slow relay C, winding of vertical magnet V to battery. The vertical magnet V operated in this circuit to raise the shaft and wipers to the desired level and upon the first vertical step the 65 off normal springs are shifted. Thereupon at springs N1 an alternative circuit is completed over armature c1 for the subsequent impulses to the vertical magnet, while at springs N2 a point is completed in the circuit of the release magnet Z. At the end of the train of impulses relay C restores and at 70 its armature c1 transfers the impulsing circuit to the rotary magnet so that the next 75 series is transmitted over armature g6, wind- 80

ing of slow relay E, armature h_5 , winding of rotary magnet R to battery. The rotary magnet R is accordingly operated to rotate the wipers into engagement with the required set of contacts and relay E remains energized throughout the train of impulses and at armature e_1 shunts armature g_6 in case relay G should be operated due to wiper P passing over busy contacts, at armature e_3 opens a point in the circuit of the party line discriminating relay PA, and at armature e_4 opens a point in the busy tone circuit. Moreover relay E at armature e_5 opens a point in the circuit of the lower winding of relay G and at armature e_2 connects the upper winding of this relay over armature h_3 and its back contact to the test wiper P.

Consider first the case of a call to an ordinary subscriber in which the wanted line is busy; in this case relay G is energized when the wipers come to rest from earth on the busy test contact, and at armature g_3 prepares a locking circuit for itself, at armature g_2 opens a further point in the circuit of relay PA, at armatures g_4 and g_5 prepares points in the code ringing circuit which are of no utility in the present instance, at armature g_6 opens a point in the circuit of the rotary magnet R, at armature g_7 opens a point in the circuit of the minor switch rotary magnet MR, and at armature g_8 connects up busy tone from conductor 15 to conductor 11 whence it is transmitted to the calling party's instrument to provide an audible indication that the called line is busy. Upon the release of relay E after its slow period, the locking circuit over armature g_3 is completed and relay G remains locked up dependent on armature b_4 . The calling subscriber on hearing the busy tone will realize that he cannot obtain connection with the desired party and will replace his receiver, thereupon opening the circuit of relay A which releases and opens the circuit of relay B. When relay B releases, at armature b_4 relay G is unlocked, at armature b_1 earth is removed from the release trunk conductor 12 to permit the preceding switches to release and at armature b_2 a circuit is completed for the release magnet Z which operates to restore the switch to normal in the usual manner.

Consider now the case in which the wanted party is idle when his line is connected with; in this case relay G is de-energized when the switch comes to rest, and accordingly when relay E de-energizes, a circuit is completed from earth, armatures b_4 and g_3 , lower winding of switching relay H, armature e_2 , test wiper P and by way of the cut-off relay and rotary magnet of the called party's line switch to battery. Relay H and the cut-off relay energize in series in this circuit and the latter clears the called line of its normal battery and earth connection. Relay H at armature h_1

completes a locking circuit for itself over its upper winding, at armature h_2 connects up a small condenser RB to permit a small amount of ringing current to leak back and give the calling party ring back tone, at armature h_3 prepares a locking circuit for relay G, at armature h_4 opens a point in the busy tone circuit, at armature h_5 opens the impulsing circuit for the rotary magnet R, at armatures h_6 and h_7 connects the speaking leads through the wipers + and -, and at armature h_8 connects direct earth to the test wiper P in order to busy the line and hold operated the called party's cut-off relay. Intermittent ringing current is now connected up from conductor 17 over armatures pa_2 and g_4 , left-hand winding of relay F, armatures f_3 and h_7 , negative wiper and bank contact, over the called line to the positive wiper, armatures h_6 , f_2 , g_5 and pa_1 , ring return resistance 18 to battery, thereby signalling the wanted party in the usual manner. When the wanted party replies, the direct current bridge thereupon completed across the speaking leads serves to operate relay F by way of its left-hand winding and at armature f_1 it completes a locking circuit for itself and at armatures f_2 and f_3 connects the speaking conductors to the back bridge relay D. Relay D on operating at its armature d_1 opens the start circuit to the ringing and tone current generator and may also reverse the speaking leads for supervisory purposes. Conversation may now take place between the calling and called parties during which the battery feed to the respective parties is supplied by relays A and D. At the end of the conversation when the calling party replaces his receiver, relay A de-energizes and at its armature a_1 releases guard relay B whereupon release of the switch takes place in the manner previously described.

Consideration must now be given to the establishment of a connection with a party line subscriber. It will be assumed that at the end of the second series of impulses transmitted to the switch the wipers are set on the contacts associated with a party line subscriber whose line is idle at this time. In this case relay H will be operated as previously explained in series with the called party's cut-off relay and in addition the auxiliary test wiper P1 will encounter earth, by means of which the party line discriminating relay PA will be operated upon the release of relay E after its slow period. Relay PA upon operating, at its armatures pa_1 and pa_2 opens the normal ringing circuit of the switch and at its armature pa_3 closes a point in the circuit of the magnet MR of the auxiliary minor switch. Since in the system considered numbers of party line subscribers comprise one more digit than those of individual line subscribers the calling party will dial a further digit which serves for selection of the

appropriate ringing code. These additional impulses effect the operation of the minor switch magnet in the circuit: earth, armatures a_1 and b_2 , off normal springs N_1 , armatures c_1 and g_6 , winding of relay E , armatures g_7 and p_{a3} winding of magnet MR to battery. Assuming that this final digit is 1 the wipers of the minor switch will be advanced to the set of bank contacts connected to the code ringing set shown in Fig. 2. It will be seen that the arrangements are suitable for up to ten parties on a line, the bells at the various substations being connected between one or other speaking lead and earth. Five code 10 ringing sets similar to that shown in Fig. 2 are provided each arranged to send a different distinctive code by suitable wiring of the banks, and the code ringing sets may be common to all the connectors such as that 15 shown in Fig. 1. Upon the release of relay E at the conclusion of the final train of impulses a circuit may be traced from earth by way of the low resistance winding of relay AA , Fig. 2, first bank contact and wiper 21 20 of the code ringing switch CR , conductor 24, first bank contact and wiper S of the minor switch, armatures b_5 , e_5 and f_4 , lower winding of relay G to battery. Relay G upon 25 operating, at armature g_1 completes a locking 30 circuit over its upper winding and at armature g_2 opens the circuit of relay PA which releases and disconnects the minor switch magnet MR at armature p_{a3} thereby preventing any further impulses from the subscriber's 35 calling device from again operating the minor switch. Furthermore, relay G at its armatures g_4 and g_5 transfers the ringing circuit to the wipers PR_1 and PR_2 of the minor switch to permit code ringing to take place 40 from the selected code ringing set.

Referring now more particularly to Fig. 2 relay AA , which is operated in series with relay G , at its armature a_1 connects slow earth pulses over conductor 25 to the driving magnet DM of the switch CR . Accordingly the magnet commences to step the wipers 45 21-23 of the switch CR round the bank contacts and at the conclusion of the first step the initial energizing circuit of relay AA is opened and the relay releases thereby opening its contacts a_1 . The switch continues to step however since at this time relay AB is operated over wiper 23 and shunts armature a_1 at armature a_2 . No further circuit 50 changes will take place until wiper 22 encounters bank contact 7, whereupon a circuit is completed for relay AC which operates and locks up over its armature a_1 to earth at armature a_2 . Relay AC upon operating extends the earth pulse circuit to relay AE so that upon the reception of the next earth pulse relay AE will operate and complete the following ringing circuit: continuous ringing from earthed generator by way of conductor 26, armature a_1 conductor 27, bank

contact 1 and wiper PR_2 of the minor switch MS , armatures g_5 , f_2 , and h_6 , positive wiper and bank contact called subscriber's instrument to earth.

By this means the wanted party's bell is rung for the duration of one earth pulse at the conclusion of which the wipers of the code ringing switch CR will be advanced to contact 8 and relay AE releases and opens the ringing circuit at armature a_1 . When earth is next applied to conductor 25, relay AE will again be operated in parallel with the driving magnet DM and ringing current will again be connected up over the circuit previously traced. This cycle of operations is again repeated and wiper 22 of the code ringing switch CR then comes into engagement with bank contact 10, whereupon relay AD will be operated and at armature a_1 will open the circuit of relay AE . Accordingly for the duration of the next earth pulse relay AE will be prevented from operating and ringing of the called party's bell will not take place during this period. At the conclusion of this earth pulse the wipers of the code ringing switch will be advanced to bank contacts 11 in which position relay AD will release and the circuit of relay AE is again extended to the conductor 25. Hence upon the reception of the next two earth pulses, relay AE will be operated in synchronism to connect up two further ringing pulses to the wanted subscriber's instrument. The wipers of the code ringing switch will then have moved into position 13 in which the circuit for relay AB is opened and it releases thereby releasing relay AC which opens the circuit for relay AE . It will be noticed, however, that assuming the connection remains set up and the called party has not replied the lower winding of relay G will be connected over wiper 21 and bank contact 13 in series with low resistance relay AA to earth and upon operation of the latter relay, interrupted earth will again be connected to the driving magnet DM by way of armature a_1 . Since the wiring of the two halves of the banks of the switch CR is similar, the operations above described will be repeated and a code consisting of 3 rings, a short pause, 2 rings and a long pause is sent out continuously as long as conditions remain the same. When the wanted party recognizes his particular code call he will reply by removing his receiver whereupon the direct current bridge thereupon completed across the speaking leads serves to operate relay F by way of its left-hand winding whereat relay F locks up and performs the functions already described. Moreover, relay F in operating also opens the circuit of the lower winding of relay G at armature f_4 so that when the code ringing switch has completed its ringing cycle, relay AA will not again be operated unless some other connector switch is requiring this par-

ticular code. In case the receiver is removed during the silent period, that is, while relay AE is in its normal position, relay F would then have been operated from earth over the resting contact of armature $\alpha e 1$. It should also be mentioned that in case another final selector switch should select a code ringing switch while it is in operation, there is no possibility of a mutilated ringing code being sent out since the ringing circuit for the second switch will not be completed until its associated G relay is operated, and this can only be effected by earth through the winding of the start relay AA in the code ringing switch which is only connected up by the wiper 21 at the commencement of a code ringing cycle.

In case a busy condition is encountered on a party line, relay G will be operated before relay H in order to extend the busy signal to the calling party and it will be noticed that with relay G operated the impulsing circuit for the minor switch magnet MR is opened at armature $g 7$ while similarly the circuit for the rotary magnet R is opened at armature $g 6$. Consequently the reception of the final code selecting digit under these conditions is without effect due to the opening of the impulsing circuit and the associated wipers PR1, PR2 and S remain in their normal position so that the code ringing switch is not brought into operation in these circumstances. The minor switch is restored to normal after a successful party line call by its release magnet MZ which is connected up over armature $b 3$ and off-normal springs MN1.

The final selector illustrated is not suitable for effecting the completion of revertive calls and assuming that other numerical switches precede this switch in the train, special revertive call switches would be accessible from a particular level of one of these switches in response to the dialling of a special revertive call number. The revertive call switch may then respond to the last two digits of the number to send out the appropriate code to ring the bells of the calling and called parties.

In case, however, the switch shown is used in an exchange of less than 100 lines revertive calls may be completed by an operator who is conveniently reached in response to the dialling of the digit "0". In this case the dotted connections shown in Fig. 1 are provided, the additional off-normal springs N3 serving to disconnect dial tone over lead 14 as soon as the switch steps off-normal. In response to the dialling of "0" the switch is raised to the tenth level whereupon normal post springs NPS1 and NPS2 are operated, the former connecting earth to discriminating lead 40 and the latter connecting up ring-back tone to notify the calling party that the operator is being signalled. The operator is provided with a full multiple of all the lines and the

earthing of lead 40 lights a lamp associated with the calling party's jack. The operator on seeing the lamp light plugs in to the jack in order to ascertain the subscriber's wishes, this operation energizing a relay connected to the sleeve of the jack which effects the release of the final selector switch and also connects earth to the private normal conductor to busy the line.

On hearing that a revertive call is required the operator will ask the calling party to hang up his receiver and will then send out the ringing code for the desired party. When he replies, the calling subscriber will again remove his receiver and conversation may take place, battery feed for both parties being supplied from the operator's cord circuit.

What I claim is:—

1. In a telephone system, an automatic numerical switch having access to different classes of lines, means for operating said switch responsive to a plurality of digits of a called telephone number to seize one of said lines, and means operated over a wiper of said switch only in case the seized line is of a particular one of said classes for preparing said switch to respond to a further digit.

2. In a telephone system, a connector switch, means for operating said switch responsive to a plurality of digits to connect with a desired called line, a selective ringing switch associated with said connector, and means for operating said selective ringing switch responsive to a further digit only in case said plurality of digits were of particular predetermined values.

3. In a telephone system, a connector switch having access to individual and party lines, means for operating said switch into engagement with one of said lines, means for ringing the called line in case an individual line is connected with, and means effective in case a party line has been connected with for disabling said ringing means and for rendering said switch responsive to a further digit.

4. In a telephone system, a connector switch having access to subscribers' lines, means responsive to two digits of a called number for operating said switch into engagement with one of said lines, means for automatically connecting ringing current to the called line, and means effective in case said two digits are of particular predetermined values for disabling said ringing means until a third digit has been received.

5. In a telephone system, a connector switch having access to individual and party lines, means for operating said switch into engagement with one of said lines responsive to two digits of a called number, means for ringing an idle individual line when connected with, and means controlled over a wiper of said switch when the switch is operated into engagement with an idle party line for dis-

abling said ringing means and for preparing said switch to respond to a further digit.

6. In a telephone system, a connector switch having access to individual and party lines, means for operating said switch into engagement with one of said lines, means for ringing the called line in case an individual line has been connected with, means effective in case a party line is connected with for disabling said ringing means and for rendering said switch responsive to a further digit, a plurality of code ringing switches, and means responsive to said further digit for selecting the proper code ringing switch to signal the wanted subscriber on the party line.

15 7. In a telephone system, a connector switch having access to individual and party lines, means for operating said switch into engagement with one of said lines, a busy relay operated in case the called line is busy to connect busy tone to the incoming line conductors, means for automatically connecting ringing current to an idle individual line when connected with, means effective in case 20 an idle party line has been connected with for disabling said ringing means and rendering said switch responsive to a third digit, and means for operating said busy relay to connect ringing current to the called party line 25 after said third digit has been received.

30 8. In a telephone system, a connector switch having access to subscribers' lines, means responsive to two digits of a called number for operating said switch into engagement with 35 one of said lines, means for automatically connecting ringing current to the called line, means effective in case said two digits are of particular predetermined values for disabling said ringing means and for preparing 40 said switch to respond to a third digit, a plurality of sources of ringing current having different characteristics, and means responsive to said third digit for selecting ringing current of the proper characteristic.

45 9. In a telephone system, a connector switch having access to individual and party lines, means for operating said switch to connect with one of said lines responsive to two digits of a called number, means for ringing an 50 idle individual line when seized, a minor switch, means effective in case an idle party line is seized for disabling said ringing means and for preparing an operating circuit for said minor switch, and means responsive to 55 the operation of said minor switch by a further digit for ringing the wanted subscriber on the party line.

60 10. In a telephone system, a connector switch having access to two classes of lines, means responsive to two digits of a called number for operating said switch into engagement with one of said lines, means for signalling said line in case it is of a certain class, and discriminating means for disabling 65 said signalling means and for preparing said

switch to respond to a further digit in case said line is of the other class.

11. In a telephone system, an automatic numerical switch having access to two classes of lines, means for operating said switch responsive to two series of impulses to seize one of said lines, an auxiliary switch associated with said numerical switch, means for operating said auxiliary switch responsive to a third series of impulses in case a line of one 70 class is seized, and means for preventing the operation of said auxiliary switch in case a line of the other class is seized.

In testimony whereof I affix my signature.

ALFRED E. FLENLEY.
